UNITED STATES PATENT OFFICE.

FRANK REVERE SPRAGUE, OF NEW YORK, N. Y.

DESIGN FOR A PORTABLE WRITING-DESK.

SPECIFICATION forming part of Design No. 35,275, dated November 5, 1901.

Application filed August 31, 1901. Serial No. 74,044. Term of patent 7 years.

To all whom it may concern:

Be it known that I, FRANK REVERE SPRAGUE, a citizen of the United States, residing at New York, in the county of New York and State of New York, have invented and produced a new and original Design for Portable Writing-Desks, of which the following is a specification, reference being had to the accompanying drawings, forming part thereof, and in which—

Figure 1 is a plan view showing my new design, and Fig. 2 is an end view thereof.

As shown in the drawings, my newly-designed writing-desk comprises a rectangular body A, formed with an approximately rectangular or octagonal panel B, approximately at the center of the rectangular body A and surrounded by a border C, which, as shown, is approximately rectangular in form. At one side of the central panel B are arranged three rectangular panels G, the central of which is longer than the others. As seen in

section, the body A is somewhat decreased in diameter in its vertically-central portion H, leaving peripheral flanges A' and A² above and below the same.

I have also shown in the drawings an ornamental wreath D and an ornamental border E, the end portions of which are formed into rectangular convolutions E².

Having thus fully described my invention, what I claim as new, and desire to secure by Letters Patent, is—

The design for a writing-desk herein shown and described.

In testimony that I claim the foregoing as my invention I have signed my name, in presence of the subscribing witnesses, this 15th day of August, 1901.

FRANK REVERE SPRAGUE.
